UNITED STATES PATENT OFFICE.

HANS H. SATER, OF MADISON, WISCONSIN.

PLOW.

SPECIFICATION forming part of Letters Patent No. 550,198, dated November 19, 1895.

Application filed February 18, 1895. Serial No. 538,844. (No model.)

To all whom it may concern:

Be it known that I, HANS H. SATER, a citizen of the United States, residing in Madison, in the county of Dane and State of Wisconsin, have invented certain new and useful Improvements in Plows, of which the following is a specification, reference being had to the accompanying drawings, in which—

Figure 1 is a side elevation of the furrow side of the plow. Fig. 2 is a side elevation showing the landside. Fig. 3 is a plan view. Fig. 4 is a sectional view showing the colter-hub and the manner of mounting the colter. Figs. 5, 6, and 7 are details of the colter-supporting yoke.

My invention relates to plows, and has for its object to provide certain improvements in the plow described in my application of even date herewith, Serial No. 533,538. These improvements relate principally to the mechanism for vertically adjusting the frame for the purpose of throwing the plow into or out of the ground and for regulating the depth of the plowing; and such improvements consist in providing improved lever mechanism for effecting such adjustments.

My invention also consists in certain improved means for securing the landside in place, which will permit of its being readily removed for certain kinds of plowing.

My improvements also relate to the devices for supporting the colter and to certain other details of construction, which will be hereinafter set forth.

In the drawings, 10 indicates the plow-beam, which, as shown in Fig. 3, is preferably of the bifurcated construction shown in my application, Serial No. 533,538, filed January 2, 1895. It may, however, be of any other approved construction.

11 indicates the plow-standard.

12 indicates the moldboard and 13 the share, which are secured to the standard in the usual way.

14 indicates a rear wheel, which is mounted on a suitable spindle 15, journaled in a sleeve 16, supported by a brace 17, which is connected to the standard 11, as shown in Fig. 1.

18 indicates a seat-bar, which is connected to the beam 10, and at its rear end receives the spindle 15, a spring 19 being arranged under the seat-bar, as also shown in Fig. 1. These parts are described in my application, Serial No. 533,538, above referred to.

20 indicates a seat, which is supported by 55 a bar 21, rising from the seat-bar 18.

22 indicates a brace, which is connected to the brace 17 and to the beam 10, as shown in Fig. 2.

The front portion of the beam is supported 60 at one side by a double crank-axle 23, which is journaled in suitable boxes 24 25, connected to the beam, as shown in Fig. 3. A wheel 26 is mounted upon one of the crank-arms 27 of said axle, as shown in Fig. 3. The opposite 65 side of the plow is supported by a vertical rod or bar 28, which carries a wheel 29. The supporting-rod 28 is connected to the beam by a laterally-projecting bar 30, as shown in Fig. 3, said bar 30 being connected to a sleeve 70 31, which encircles the bar 28, and is movable vertically thereon, as shown in Figs. 1 and 3. The bar 30 is provided with a slot 32, so that the point at which it is connected to the sleeve 31 may be adjusted, and the distance of the 75 supporting-rod 28 from the plow-beam be thereby adjusted. The sleeve 31 carries a segmental rack 33 at its rear side, as shown in Fig. 1. At the forward side of the sleeve and connected thereto is a bracket 34, as 80 shown in Fig. 1, to which is pivoted the forward bifurcated end of a lever 35, said lever being fulcrumed to a link 36, pivotally connected by a cap 37 to the upper portion of the bar 28, as shown in Fig. 1. By this construction by operating the lever 35 the sleeve 31 may be vertically adjusted upon the bar 28, thereby adjusting the beam vertically.

The lever 35 carries a dog 38, which engages the rack 33, and is operated by a hand-lever 39 and connecting-rod 40, locking said lever at different positions.

41 indicates an adjusting-lever, which is pivoted upon the lever 35, and may be locked at different positions by means of a dog 42, 95 which engages a rack-bar 43, secured to the lever 35 in a suitable position, as shown in Fig. 1. The lever 41 is connected by a connecting-rod 44 to the second arm 45 of the crank-axle 23, as shown in Figs. 1 and 3, so 100 that by operating said lever 41 the axle 23 may be rocked and the position of the landside of the plow be thereby regulated.

In order to give the axle 23 a yielding action and to avoid danger of breaking the parts 105 when the plow strikes an obstruction, a spring 46 is provided, which is mounted upon the rod 44 between the lever 41 and the arm 45,

as shown in Fig. 1. The arm 45 is also provided with a number of perforations to permit of adjusting the position at which the rod 44 is connected to it, as shown in Fig. 1. It 5 will be seen that by this construction, when desired, by operating the lower lever 35 both sides of the plow-beam may be simultaneously adjusted vertically, as for the purpose of throwing the plow into or out of the ground 10 and for regulating the depth of the plowing. By adjusting the upper lever 41 the plow may be tilted for throwing the plow out of the ground or deeper into the ground. I prefer to arrange the levers 35 41 at the angle shown 15 in Fig. 1, in order that they may be readily accessible to the operator when either walking or riding.

47 indicates the landside of the plow, which is detached from the share 13, and is secured 20 in position by braces 48 49 50, as shown in Fig. 2. The brace 48 is connected by screws or other suitable devices to the standard 11. The brace 49 is connected in a similar manner to the moldboard 12, and the brace 50 25 extends from the point of connection of the brace 49 with the moldboard to the standard 11. By this construction the landside 47 may readily be removed when desired.

51 indicates a colter, which, as shown in 30 Fig. 3, is supported by a yoke 52, connected to a laterally-projecting arm 53, secured to one member of the beam 10. The yoke 52 is adjustable laterally and is secured to the arm 53 by a clamp 54. The colter 51 is secured 35 to the yoke 52 by a shaft 55, which forms a spindle for the colter, passing through the ends of the yoke 52. At each side of the colter 51 is a conical sleeve 56, which sleeves are fixedly secured to the colter and are provided 40 with oil-ducts 57 at one side, as shown in Fig. 4. The outer ends of the sleeves 56 rest in cup-bearings 58, which in turn bear against the inner faces of the ends of the yoke 52. To hold the bearings 58 rigid, they are each 45 provided with a lug 59 on their outer faces, which lugs are adapted to fit into slots 60 in the ends of the yoke, as shown in Fig. 6. The outer faces of the ends of the yoke 52 are provided with U-shaped flanges 61, and the 50 ends of the yoke are confined tightly against the bearings 58 by nuts 62 and washers 63 between such nuts and the ends of the yoke, the washers 63 being provided with recesses 64, adapted to receive the flanges 61. The 55 nuts 62 are screwed upon the ends of the shaft 55, as shown in Fig. 4.

Within the sleeves 56 are plugs 65, and between such plugs is a spring 66, which bears against the plugs and holds them apart. The 60 plugs 65 serve as bearings for the shaft 55 and also to strengthen the sleeves 56.

That which I claim as my invention, and desire to secure by Letters Patent, is—

1. The combination with a yoke, and a shaft 65 connecting the ends of said yoke, of a colter mounted upon said shaft, sleeves mounted upon said shaft between said colter and the

ends of said yoke, plugs 65 within said sleeves, and a spring between said plugs, substantially as described. 70

2. The combination with a yoke 52 having slotted ends, of a colter, sleeves 56, caps 58 having lugs adapted to enter the slots in said yoke, a shaft connecting the ends of said yoke, and nuts 62, substantially as described. 75

3. The combination with a yoke 52, having slotted ends, of a colter, sleeves 56, caps 58 having lugs adapted to enter the slots in said yoke, a shaft connecting the ends of said yoke, nuts 62, and washers 63 between the nuts and the ends of said yoke, substantially as described. 80

4. In a plow, the combination with a beam, and furrow opening devices, of a double crank axle supporting the forward end of the beam, 85 a wheel mounted upon one of the arms of said crank axle, a vertical support for the opposite side of the beam, a lever connected to the beam and fulcrumed upon said support for raising and lowering the beam, and an adjusting lever 90 mounted upon the former lever and connected to one of the arms of said crank axle, substantially as described.

5. In a plow, the combination with a beam, and furrow opening devices, of a double crank 95 axle supporting the forward end of the beam, a wheel mounted upon one of the arms of said crank axle, a vertical support for the opposite side of the beam, a lever connected to the beam and fulcrumed upon said support for raising 100 and lowering the beam, an adjusting lever mounted upon the former lever, a rod 44 connecting said adjusting lever to one of the arms of said crank axle, and a spring on said rod, substantially as described. 105

6. In a plow, the combination with a beam, and furrow opening devices, of a double crank axle supporting the forward end of the beam, 110 a lever for raising and lowering the beam, and an adjusting lever mounted upon the former lever for rocking said double crank axle, substantially as and for the purpose specified.

7. In a plow, the combination with a beam, and furrow opening devices, of a crank axle connected to the forward portion of the beam 115 and carrying a land wheel, a lever for adjusting the beam vertically, and an auxiliary lever for adjusting the position of the land wheel, substantially as described.

8. In a plow, the combination with a beam, and furrow opening devices, of a double crank axle 23 connected to the forward portion of the beam, a wheel mounted upon said axle, a laterally projecting bar 30 connected to the beam, a sleeve 31 connected to said bar, a 125 forwardly projecting bracket 34 connected to the sleeve, a segmental rack 33 also connected to said sleeve, a lever pivoted to said bracket, and a vertical support forming a fulcrum for said lever, substantially as described.
